UNITED STATES PATENT OFFICE.

MARTIN W. FITZGERALD, OF BROCKTON, MASSACHUSETTS, ASSIGNOR TO SEARS, ROEBUCK & CO. OF MAINE, OF SPRINGVALE, MAINE, A CORPORATION OF MAINE.

SHOE UPPER.

Application filed July 16, 1924. Serial No. 726,281.

To all whom it may concern:

Be it known that I, MARTIN W. FITZGERALD, a citizen of the United States, residing at Brockton, county of Plymouth, State of Massachusetts, have invented a certain new and useful Improvement in Shoe Uppers, of which the following is a specification, reference being had therein to the accompanying drawings.

10 This invention relates to the finishing of the exposed edges of the uppers of shoes, and especially the exposed edges of women's high-grade low shoes, and has for its general object to provide a method whereby the exposed edges of the uppers of such shoes may be attractively and satisfactorily finished at a cost considerably less than that involved in producing work of equal grade by the methods heretofore usually employed.

20 The edges of the uppers of women's high-grade low shoes have heretofore usually been completed and bound or trimmed by what is known as a "French finish." In carrying out this method, a strip of binding material is laid upon the margin of the upper with one of its edges substantially registering with the edge of the upper and is sewed to the latter by a longitudinal seam located close to the superposed edges. The binding material is then folded laterally over the edge of the upper in such a manner as to conceal the seam and form a smooth and even beading or piping, and its free edge is cemented to the inner face of the upper, 30 after which it is secured in place by a second longitudinal seam. This method of finishing the edge of the upper is slow and laborious, requires highly skilled hand labor in order to produce satisfactory work, and involves three distinct operations, namely, first, 40 sewing the edge of the binding material to the edge of the upper, second, folding the binding material evenly over the edge of the upper and cementing the same in place, and, third, stitching the cemented edge of the binding material to the upper. The second of these operations requires the utmost care and skill in order to lay the binding material evenly over the 50 edge of the upper while cementing it in place without soiling, and the character of the labor required makes this operation extremely expensive. In order to overcome these objections, it has been proposed to finish the edges of shoe uppers by sewing there-

to, by means of a single longitudinal seam, a strip of binding material applied in folded position over the edge of the upper by the use of a sewing machine having a folding attachment, the seam passing through the upper and through both edges of the binding material. The results accomplished by this method, however, are very unsatisfactory, the finish produced being of rough and ragged appearance and being unsuitable for any 60 shoes except those of the cheapest and lowest grades.

65 The present invention has, therefore, for a more particular object to provide a shoe upper and a method of finishing the same in accordance with which the edge of the upper may be quickly finished at a single machine operation requiring only moderate skill and, therefore, only relatively small expense, the result being comparable to the expensive 70 "French finish" and being entirely satisfactory for shoes of the best grades.

75 The foregoing and other objects of the invention will best be understood from the following description of certain operations 80 and resulting products by which said invention may be carried into effect, all as illustrated in the accompanying drawings. It will be understood, however, that the particular operations, devices, materials, and results described and shown have been chosen for illustrative purposes merely, and that the invention, as defined by the claim hereunto appended, may be otherwise practised 85 without departure from the spirit and scope 90 thereof.

95 In said drawings:

Fig. 1 is a side elevation of a shoe finished in accordance with the invention.

Fig. 2 is a greatly enlarged, fragmentary, perspective view illustrating a type of braid suitable for use in practising the invention.

Fig. 3 is a plan view of the guiding and stitching instrumentalities employed, illustrating the operation of attaching the finishing material or braid to the edge of the upper.

100 Figs. 4 and 5 are sections taken substantially on the lines 4—4 and 5—5, respectively, Fig. 3.

105 Fig. 6 is a greatly enlarged conventionalized or diagrammatic perspective view illustrating the completed work.

110 Fig. 7 is a view similar to Fig. 6 showing the upper lining secured in place.

Referring first to Fig. 1, there is shown therein a shoe comprising a sole B, a heel C, and an upper A including an ankle strap a. The exposed edges of the upper A, including the ankle strap, are, in accordance with the present invention, finished by the attachment thereto of a strip of suitable finishing or binding material D. As shown in Fig. 2, said binding material D may comprise a flat or unfolded strip of braid of suitable character, the braid shown consisting of two or more longitudinal parallel twisted strands 20 constituting warps with which is interwoven suitable weft material 21 which may comprise silver or gilt tinsel or threads of any desired color. In accordance with the invention, the finishing or binding material D is secured to the edge of the upper A by means of a zigzag seam E, so as to become a unitary edge portion thereof.

The zigzag seam E for attaching the braid D to the edge of the upper A may be formed by a zigzag-stitch sewing machine of any suitable type. Certain parts of such a machine are illustrated in Figs. 3, 4 and 5, wherein 22 denotes the bed plate, 23 the feed member, 24 the presser foot, and 25 the needle. These instrumentalities are adapted to the purpose of practising the invention, as illustrated in Figs. 1 to 7, by providing the bed plate 22 with a fixed tubular guide 26 for the braid D immediately in advance of the presser foot 24 and by providing the latter with a lateral guiding shoulder 27 (Fig. 5) adapted to engage the edge of said braid as the latter emerges from the guide 26.

In carrying out the method by the use of the materials and instrumentalities above described, the braid D is passed through the guide 26 and under the presser foot 24 in engagement with the shoulder 27 on the latter, and the edge of the upper A is pushed and guided by hand into abutting relationship to the free edge of the braid, forcing the latter against said shoulder, whereby said upper and braid, as fed through the machine by a feeding member 23, are guided into juxtaposition as they are connected by the zigzag seam E, the lat-

ter at one side being caused to penetrate the upper adjacent the edge thereof and at the opposite side being caused to penetrate the strip of braid intermediate the edges of the latter. The usual zigzag seam, as shown in Fig. 6, comprises an upper or needle thread e¹ and a lower or shuttle thread e² which is passed through the needle loops of the upper thread and which, when tightened by the usual takeup devices (not shown), causes the braid D to be firmly bound to the edge of the upper A so as to finish the same in an attractive way, this result being accomplished by a single passage of the work through the machine while guiding the parts in a simple manner not requiring any high degree of skill. If desired, and as shown in Fig. 7, a lining F may be secured in the usual positon to the upper by means of the usual longitudinal seam G connecting said upper and lining adjacent their upper edges, the lining in this instance preferably extending up a short distance above the abutting edges of the upper A and the braid D, and the seam G being located coincident with or immediately adjacent the inner edge of the zigzag seam E.

The resulting finish shown in Fig. 1, and diagrammatically on a considerably enlarged scale in Fig. 6, is suitable for shoes of the best grades and, as above explained, can be quickly and easily applied at a single operation and by the exercise of very little skill. The braid D may be of any color and composed of any material suitable to the class of work in connection with which it is used and the thread forming the seam E may be of the same color as the braid or otherwise as may be preferred.

Having thus described my invention, what I claim is:

A shoe comprising an upper having at the free edge thereof a pair of parallel braids connected together and attached to the upper by a single zigzag seam, each stitch thereof passing centrally between said braids and through the upper at one point only.

In testimony whereof I affix my signature.

MARTIN W. FITZGERALD.
